US00D955651S

(12) **United States Design Patent** (10) Patent No.: **US D955,651 S**
(45) Date of Patent: **** Jun. 21, 2022**

(54) **SURGICAL HELMET**

(71) Applicant: **Stryker Corporation**, Kalamazoo, MI (US)

(72) Inventors: **Matthew Van Nortwick**, Ann Arbor, MI (US); **Benjamin Edinger**, Grand Haven, MI (US)

(73) Assignee: **Stryker Corporation**, Kalamazoo, MI (US)

(**) Term: **15 Years**

(21) Appl. No.: **29/744,305**

(22) Filed: **Jul. 28, 2020**

Related U.S. Application Data

(63) Continuation of application No. 29/700,254, filed on Jul. 31, 2019.

(57) **CLAIM**

The ornamental design for a surgical helmet, as shown and described.

DESCRIPTION

FIG. 1 is a top, front left-side perspective view of a surgical helmet showing our new design;

FIG. 2 is a bottom left-side perspective view thereof;

FIG. 3 is a front right-side perspective view thereof;

FIG. 4 is a front view thereof;

FIG. 5 is a right-side view thereof;

FIG. 6 is a left-side view thereof;

FIG. 7 is a top view thereof;

FIG. 8 is a bottom view thereof; and,

FIG. 9 is a rear view thereof.

The broken lines depicting portions of the surgical helmet form no part of the claimed design.

1 Claim, 9 Drawing Sheets
